UNITED STATES PATENT OFFICE.

ANTHONY LA FRANCIS, OF NEWARK, NEW JERSEY.

DESIGN FOR A HARNESS-TRIMMING CHAIN.

SPECIFICATION forming part of Design No. 17,356, dated May 24, 1887.

Application filed February 23, 1887. Serial No. 228,619. Term of patent 7 years.

To all whom it may concern:

Be it known that I, ANTHONY LA FRANCIS, a citizen of the United States, residing at Newark, in the county of Essex and State of New Jersey, have invented and produced a new and original Design for Harness-Trimming Chains; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front elevation, and Fig. 2 is a plan, of a bridle-front having the newly-designed harness-trimming chain. Fig. 3 is a plan and edge view of a link in detail. Figs. 5, 7, and 8 are plans of chains embracing the design; and Figs. 4 and 6 are side views to illustrate configurations of linkss shown in Figs. 5 and 7.

In the drawings, A represents an ordinary piece of harness, and B a mounting or trimming chain, comprising a series of elliptical links elongated transversely to the length of the chain, and, alternating with said links, flat-

tened strap-like links the upper surfaces of which are ornamented with regular lines of bosses.

The leading feature of the design consists in a trimming-chain comprising the series of elliptical links elongated transversely to the length of the chain, having between said links a series of flattened strap-like links the upper surfaces of which are ornamented with regular lines of bosses, as set forth.

What I claim as new is--

The design for the harness-trimming chain herein shown and described, the same consisting of the chain which comprises the series of elliptical links elongated transversely to the length of the chain, having between the said links a series of flattened strap-like links the upper surfaces of which are ornamented with regular lines of bosses, as set forth.

In testimony that I claim the foregoing I have hereunto set my hand this 15th day of December, 1886.

ANTHONY LA FRANCIS.
